Application August 3, 1940, Serial No. 350,976

15 Claims.

(Cl. 198—27)

The present invention relates to apparatus for handling, coating and treating articles of manufacture, such as containers. More particularly, the invention provides apparatus for coating with wax or the like the interiors of metallic containers, such as beer cans.

In the manufacture of beer cans and similar containers, the containers are lined with a wax-like coating material to prevent contact of the contents of the containers with the metallic walls thereof. It is of paramount importance that the lining be continuous and of uniform thickness. It is also important that the continuous lining be relatively thin for the sake of economy, yet cover all portions of the interior surface of the container. With containers having cylindrical bodies, conical upper ends and bottom end members double-seamed to the bottom ends, it is desirable to have an excess of coating material at the bottom along the line of the double-seam, to make certain that the seam is sealed against the entrance of beer or the like into the folds of the seam.

It is also of importance to prevent the coating material from running or spreading onto the pouring lip or the neck of the container, since wax at these points presents an unattractive, messy appearance and retards sale of the packaged goods.

It is an object of the invention to provide improved means for handling, coating and treating a line of containers so as to provide a uniform, continuous, relatively thin coating of wax-like material on the interior surfaces thereof. It is a further object of the invention to provide improved means for settling the wax into the double-seams at the bottom ends of the containers and to provide a slight excess adjacent thereto. Another object of the invention is to so handle the containers as to prevent the wax from running over onto the pouring lip or the neck of the containers.

A further object of the invention is to preheat the containers to a desired degree, to prevent premature cooling and hardening of the wax and to facilitate the coating of the surfaces of the containers with the hot liquid wax-like material.

It is a further object of the invention to provide improved means for draining the excess wax from the interior of the containers so as to produce a uniform coating of desired, controlled thickness.

A further object of the invention is to provide improved means for handling a line of containers,

for inverting and reverting them and for transferring them from one apparatus to the next.

Other and further objects and advantages of the invention will be apparent from a consideration of the following description of the specific embodiment of the invention shown in the accompanying drawings, in which—

Figure 1 is a diagrammatic plan view of the apparatus as a whole.

Figure 2 is an enlarged plan view, somewhat diagrammatic in character and with certain parts removed for the sake of clarity, showing an infeed transfer table and inverting mechanism.

Figure 3 is a fragmentary, vertical section, on a reduced scale, taken substantially on line 3—3 of Figure 2.

Figure 4 is a similar vertical section, with certain parts added and others omitted, taken on line 4—4 of Figure 2.

Figure 5 is an enlarged, fragmentary vertical section illustrating the transfer of containers to the preheating oven conveyor.

Figure 6 is a vertical section through the preheating oven.

Figure 7 is a fragmentary plan view of one of the oven conveyor chains.

Figure 8 is a vertical section adjacent the discharge end of the wax drain oven, showing the take-out mechanism.

Figure 9 is a fragmentary plan view of the apparatus shown in Figure 8.

Figure 10 is a detail section showing the drive for the dial of Figures 8 and 9.

Figure 11 is a vertical longitudinal section at the entrance end of the wax settling oven, and

Figure 12 is a vertical transverse section through that oven.

General description

Although not confined to such use, the apparatus of the present invention is adapted to coat with wax, the interiors of drawn seamless containers of the type shown in the pending application of Calleson et al., Serial No. 334,876, filed May 13, 1940. A line of such containers 15, having cylindrical side walls 16, conical upper ends 17, terminating in necks having crown finishes 19 at their upper ends and bottom end members 20 double-seamed to their bottom ends, are conducted by gravity down a chute 21, as shown in Figure 1 and 2. The containers are transferred by a vertically disposed dial 22 to a plurality of tilting brackets 23 carried by a chain 24 trained about a plurality of sprockets herein-after described. During their movement in the

brackets 23, the containers 16 are swung downwardly to an inverted vertical position and are then transferred to holders 25 carried by a conveyor chain 26 trained for movement on a horizontal path through a preheating oven 27. At the discharge end 28 of this oven, the chain 26 carries the containers around a sprocket 29 past an infeed transfer position 30 adjacent a coating machine 31, where the containers are transferred to holders associated with the latter machine.

The details of construction of the inside waxing machine 31 are not shown and described herein, since a machine of the type shown in the application of Goebel and Rau, Serial No. 151,758, filed July 2, 1937, may be employed, preferably in the modified form shown in the application of Gladfelter and Duhan, Serial No. 348,306, filed July 29, 1940. Reference is made to those applications for a complete disclosure of a suitable inside coating machine which may be used with the devices shown in detail herein.

At the discharge station 32 of the coating machine 31, the coated cans are picked up by holders 33 associated with a conveyor chain 34 which leads them around a sprocket 35 into the entrance end 36 of a wax drain oven 37. The containers move through this oven, around a sprocket (not shown) at the other end thereof and pass out through the discharge opening 38 to a discharge position 39, where they are released from the holders 33 and fall by gravity to an inclined position into peripheral pockets associated with an outfeed dial 40, the latter being mounted for rotation on an inclined plane.

The containers are carried around to the lowermost point in the path of movement of the dial 40 and are ejected from the pockets thereof and received in the entrance end of a twister 41. The twister is inclined downwardly, so that the containers roll or slide under the influence of gravity therealong. During this movement, they are moved from an inclined, neck-down position, as shown at the bottom of Figure 8, to a vertical, neck-up position, as shown in Figure 11. At the discharge end of the twister, the upright containers are deposited upon the upper flight of a conveyor 42 trained for movement through a wax settling oven 43. During their passage through this oven, a portion of the wax on the side walls of the containers flows downwardly under the influence of gravity to provide a slight excess adjacent the double-seam at the bottom of the container, to effectively seal the same. Also, the wax on the side walls and the inner surfaces of the necks 17 has an opportunity to distribute itself evenly. The containers are delivered at the discharge end 45 of the settling oven 43 to any appropriate transfer device or conveyor which carries them through a cooling flight to a packing station or the like, where the containers may be placed in shipping cartons or otherwise disposed of.

The infeed dial and container inverting table

As stated above, the containers 16 move in a line under the influence of gravity down a chute 21. At the lower end of the chute, the containers are deposited, one by one, in the pockets 50 of the vertically disposed infeed dial 22, mounted for rotation on a shaft 51, journalled in bearings 52, 53 carried by the upper ends of vertically disposed shafts 54, 55, supported at their lower ends upon an appropriate base 56 (Figure 3). Rotation is imparted to the shaft 51 by spur gears 57, 58, the latter being fast upon a stub shaft 59

having a sprocket 60 on its lower end, driven as hereinafter explained.

Each container receiving pocket 50 has a plurality of magnetic plugs 61 associated therewith, to hold the containers in the pockets as the dial rotates to bring the containers to the lowermost position, above the tiltable brackets 23, referred to above. Appropriate stripper devices, not shown, cause the containers at this position to be transferred from the pockets 50 to the pockets associated with the brackets 23, the latter having magnetic plugs 62 associated therewith to facilitate the transfer and to hold the containers in the pockets when the brackets assume a vertical position, as hereinafter explained.

The chain 24 carries a plurality of vertically disposed plates 65 to which the brackets 23 are pivotally mounted at 66. At the other end of each bracket, there is a roller 67 in engagement with a guide rail 68 which has an upwardly disposed portion 68a, adapted to support the brackets in horizontal position, a downwardly inclined portion 68b which permits the brackets to swing downwardly under the influence of gravity to a vertical position and another inclined portion 68c which again raises the brackets to their horizontal position. At the transfer position, hereinafter explained and as shown in Figure 5, the rollers 67 are guided in a fixed upwardly facing channel member 69.

The chain 24 is trained about four horizontally disposed sprockets 70, 71, 72, 73, mounted on vertically disposed shafts 70'-73', respectively. The shafts 70, 70' are supported and journalled for rotation in horizontally disposed bridge members 74, 75 having their ends supported upon rods 76, 77 carried in turn by end brackets 78, 79, centrally supported upon posts 80, 81 carried by the base 59. A sprocket chain 82 is trained about a sprocket on the lower end of the stub shaft 70' and about the sprocket 60, to drive the shaft 59 and the vertically disposed dial 22.

The shaft 73' (Figures 2 and 4) for the sprocket 73 extends downwardly through a transverse bracket 83 and is connected by a coupling 84 to a vertical shaft 85 journalled in bearings 86, 86' carried by a frame member 87. A gear 88 on the shaft 85 is in mesh with a gear 89 on a stub shaft 90 having a gear 91 on its other end, in mesh with a gear 92 on a main drive shaft 93. Hence, the sprocket 73 is positively driven and, in turn, through the chain 24, drives the sprockets 70, 71, 72 and, through the chain 82, the infeed dial 22.

Stub shaft 72' for the sprocket 72 is journalled in a bracket 95, the brackets 83 and 95 being supported by vertical posts 96, 97 and being interconnected by rods 98, 99 and a transverse bridge 100.

From the foregoing description it will be apparent that the chain 24 and the infeed dial 22 are driven in unison, so that, as each pocket 50 in the dial approaches the discharge position, a bracket 23 is in position to receive a container therefrom. As the chain moves around and approaches the preheating oven chain 26, the brackets 23 move downwardly to the vertical position shown in Figure 5 and the containers are transferred to the holders 25 associated with the chain 26, as hereinafter explained.

The preheating oven and conveyor

As shown in Figure 1, one end of the preheating oven 27 is stepped back to provide an exposed conveyor portion, opposite the infeed dial and

container inverting table. The conveyor chain 26 is trained about an exteriorly disposed sprocket 29 and, at the other end of the oven, about an interiorly disposed sprocket, not shown. The transfer of containers from the brackets 23 to the holders 25 is effected between the positions 105 and 106, where the brackets and holders move along parallel paths with their respective chains 24, 26.

As shown in Figures 5, 6 and 7, alternate links of the chain 26 carry upwardly and downwardly projecting flange members 107, 108, to which are secured the holders 25, integral with brackets having upper and lower blocks 109, 110 secured by screws to the flanges 107, 108. Each lower block is extended downwardly to provide apertured bosses 111, carrying a shaft 112 and a supporting roller 113, riding upon a track 114 associated with angle members 115 and having side guide strips 116 associated therewith. The upper block 109 of the bracket is extended upwardly to provide a vertically disposed sleeve portion 117 carrying a vertical shaft 118 upon which a horizontally disposed guide roller 119 is journaled, the roller being disposed within a downwardly facing guide channel 120, carried by the oven framework. The sleeve portion 117 is shaped to provide a horizontal bore 121, in which a pivoted pin 122 for a can holding clamp 123 is mounted, the clamp being urged downwardly into clamping relation by a leaf spring 124 disposed under the tail 125 of the clamp.

As shown in Figure 6, the angle iron base 115 for the track 114 extends longitudinally of the oven beneath both flights of the conveyor chain 26 and is supported by transverse members 126, supported by hangers 127, secured to the upper transverse frame members 128 of the oven framework.

The oven comprises insulated bottom and side walls 130, 131 supported upon a framework 132 and reinforced internally by vertical side frame members 133 and the upper, transverse members 128 which support the lower tracks 114, as previously described, as well as the guide channels 120, the latter being secured to the lower flanges of angle members 134. A removable, insulated cover 130', made in sections to facilitate access to the oven, closes the upper end thereof.

The oven is preferably maintained at the desired elevated temperature by heated air conducted thereto by a conduit 135, having a plurality of openings 136 in the side walls thereof. Means for adjusting the size of the openings at various points throughout the length of the oven are provided. As shown in Figure 6, longitudinally extending closure plates 137, which may take the form of angle irons connected by transverse members 138, are adapted to be raised and lowered by pins 139 threaded in nuts 140, welded to the transverse members 138, and extending downwardly through sleeves 141 in the floor of the oven. Collars 142 on the pins 139 prevent relative longitudinal movement of the pins and the floor of the conduit 135. Hence, when the pins are rotated the closure plates 137 are raised or lowered relative to the conduit 135, to control the delivery of heated air from the openings 136 in the conduit to the interior of the oven.

As shown in Figure 7, the clamps 123 are provided with downwardly projecting, arcuate ribs 145 adapted to engage the double-seam 20 of the containers 16. The tail 125 of each clamp is provided with an outwardly facing groove 146, adapted to engage the undersurface of a sta-

tionary cam 147, adjacent the discharge and transfer positions. As the holders 25 approach the brackets 23, the clamp 123 is in the raised position shown in dotted lines in Figure 5, as a result of the action of a lowered portion of the cam 147. As the holders and brackets move together, a raised portion of the cam 142 is encountered thereby enabling the spring 124 to urge the clamps downwardly to the full line position shown in Figure 5, whereupon the containers are clamped firmly against the holders 25. Hence, as the brackets move away from the holders, the containers are removed therefrom and travel with the holders into and through the preheating oven, being supported as shown in Figure 6.

At the position 30, where the containers are transferred to the inside coating machine 31, the cam 147 quickly raises the clamps 123 and the containers are grasped by means associated with the can holders in the coating machine, as described in the aforesaid application of Gladfelter and Duhan, Serial No. 348,306, filed July 29, 1940.

The wax drain oven, conveyor and takeout means

As stated above, the containers are transferred from the wax coating machine 31 to the holders 33 associated with the wax drain oven conveyor chain 34 at point 32 (Figure 1). Since the holders 33 associated with the chain 34 are substantially identical to the holders 25 carried by the preheater chain 26, they need not be further described. At the point 32, the clamps 123' are snapped down upon the bottom seams 20 of the containers in the wax coating machine and thereafter move with the wax drain oven conveyor chain. The wax drain oven may be similar in construction to the preheating oven, with the addition of appropriate trough means to receive the wax that drains from the containers. As indicated in Figure 8, the conveyor chain 34 is supported upon angle members 115' by rollers 113' and is guided by a channel member 120', as previously described.

At the discharge point 39, the clamps 123' are raised by a downwardly projecting portion of a cam bar 147'. Since the holders 33 terminate at their lower ends in frusto-conical inclined ends 33a, disposed in engagement with the conical ends of the containers, when the up-ended bottoms of the containers are so released, they fall or tilt outwardly and downwardly under the influence of gravity, as shown in Figure 8, where they are received in pockets 150 in the periphery of the outfeed dial 40. The dial is mounted for rotation on an inclined plane and is supported by a shaft 151, journaled for rotation in a casing 152, carried by a frame 153. Each pocket 150 has a magnetic plug 154 associated with its bottom, to hold the containers therein as they are rotated to a position below the dial. The shaft 151 has a pinion 155 at its lower end, in a housing 156 at the end of the casing 152 and in mesh with a gear 157 on a drive shaft 158, which may be connected to the drive shaft 93, previously described, or may be driven from the same or an independent source of power.

An ejector spring 160, supported by a stationary bracket 161, bears against the face of the dial 22 and is positioned to engage the double-seams 20 of the containers in the pockets 150 to force the containers outwardly therefrom and into the upper end 165 of the twister 41.

As a result of the construction just described,

the drained containers are released at a predetermined point in their travel with the wax drain oven conveyor chain, whereupon they fall gently by gravity through an arc of substantially 45°, into the pockets of the outfeed dial. They are held in the pockets by the magnetic plugs 154 until they are forced outwardly therefrom by the spring ejector, whereupon they swing downwardly into the twister and are carried away under the influence of gravity to the settling oven.

The settling oven and its infeed device

As shown in Figures 1, 8, 9 and 11, the twister 41 which receives the containers from the dial 40, comprises a plurality of parallel bars 170, secured together by transversely arranged strips 171. At the entrance end of the twister, bars 170a are positioned below the side wall of the containers, while bars 170b, 170c are disposed opposite the bottoms and neck ends thereof, respectively. These bars extend downwardly and are bent laterally, so that the bar 170b at the discharge position (Figure 11) is below the containers while the bars 170a are at one side thereof. Hence, as the containers roll or slide down along the bars 170a, with their bottoms engaging the bars 170b, they are uprighted, from the inverted, inclined position represented by the upper can in Figure 8 to the position of the lower can in that figure and the can in Figure 11.

The bars of the twister terminate adjacent the intake end of the conveyor 42 in the wax settling oven 43. This conveyor preferably comprises a plurality of links having plane upper surfaces for the reception of the lower ends of the cans, the conveyor being trained for movement through the oven with an upper active flight 175 supported upon guide rails 176 and a lower inactive flight 177 therebelow, supported upon a plate 178. As indicated in Figure 12, guide strips 179 are provided along the upper active flight of the conveyor, to prevent inadvertent displacement of the containers.

The wax settling oven comprises insulated bottom and side walls 180, 181 and removable insulated cover section 182. A conduit 183 for heated air is disposed interiorly of the oven chamber and appropriate control means may be provided for the delivery of air therefrom.

During their passage through the wax settling oven, the containers are maintained at a sufficiently elevated temperature to enable the wax to distribute itself evenly over the interior surfaces of the containers and to collect adjacent the double-seams at the bottom thereof, to seal the same and prevent the contents of the containers gaining access to the folds of the metal in the seam.

At the discharge end 45 of the wax settling oven, the containers are removed by any appropriate means and conveyed to the next point in the line, for instance, to a packing station.

We claim:

1. In combination, a conveyor for moving a line of hollow articles through a preheating oven prior to their delivery to a coating machine, said conveyor having vertically disposed article holders thereon adapted to support the articles in inverted position, an infeed conveyor trained for movement adjacent the path of movement of the holders, a plurality of tilttable brackets carried by the infeed conveyor, means for delivering a line of horizontally disposed articles to said brackets when in a horizontal position, means for swing-

ing the brackets to an inverted position as they approach the holders, and means for transferring the inverted articles to those holders.

2. In combination, a conveyor trained for movement through a container pre-heating oven, vertically disposed article holders on the conveyor, an infeed conveyor trained for movement adjacent the path of movement of said holders, a plurality of tilttable brackets carried by the infeed conveyor for swinging movement from a horizontal to a vertical position, a vertically disposed dial above the infeed conveyor and adapted to deliver a line of horizontally disposed articles to said brackets when in the horizontal position, means for swinging the brackets from the horizontal to a vertical position, and means for transferring the articles from said brackets when in the vertical position to said vertically disposed holders on the first-mentioned conveyor.
3. In combination, a conveyor trained for movement through an oven or the like, a plurality of vertically disposed article holders thereon, an inclined gravity chute down which the articles move in horizontal position, a vertically disposed article receiving dial at the discharge end of the chute having horizontally arranged peripheral pockets therein, an endless chain trained for movement on a horizontal path and having one flight disposed below the dial and another adjacent the oven conveyor, tilttable brackets carried by the chain, means maintaining the brackets in horizontal position below the dial to receive articles therefrom, means for swinging the brackets to a vertical position and for maintaining them in that position during their movement adjacent the oven conveyor, whereby the vertically disposed articles in the brackets may be transferred to the vertically disposed holders on the conveyor.
4. Means for handling and conveying a line of containers, comprising a conveyor trained for movement along a horizontal path and having a plurality of vertically disposed article receiving pockets, clamps adjacent the pockets adapted to hold the articles in inverted position therein, a gravity chute down which the articles move in horizontal position under the influence of gravity, a vertically disposed dial mounted for rotation on a horizontal axis below said chute and having peripheral pockets adapted to receive articles from the chute, a conveyor having tilttable brackets mounted thereon guided for movement in horizontal position below the dial to receive articles therefrom and for movement in vertical position parallel to and adjacent the first-mentioned conveyor, and means for moving said clamps into clamping relation to the articles in the brackets to effect transfer of the articles therefrom to said pockets.
5. In combination, a conveyor chain having a plurality of vertically disposed pocket members secured thereto, clamps pivoted to the pocket members for vertical swinging movement between an operative container-clamping position and an inoperative position, means urging the clamps downwardly to the former position, a plurality of tilttable brackets, means for moving the same in horizontal position past a container receiving station, means for tilting the brackets to a vertical position in parallelism with the pocket members on said conveyor chain, means for moving the brackets in the latter position with the pockets, and means for moving said clamps downwardly into clamping relation to the containers in the

brackets in the last-mentioned position to transfer the containers from the brackets to the pocket members.

6. In an apparatus of the class described, an endless chain trained for movement through an oven chamber or the like and having portions thereof disposed exteriorly of the chamber, a chain supporting track in said chamber, a plurality of rollers carried by the chain and supported upon said track, pocket forming members carried by the chain having surfaces adapted to engage the side walls of the containers, bottom end engaging clamps carried by the members, means for urging the clamps downwardly to clamp the containers in the pocket members against said side wall engaging surfaces, infeed and outfeed stations adjacent exteriorly disposed portions of the conveyor and means for raising the clamps to release position adjacent said stations.

7. A conveyor for a line of containers having cylindrical side walls and bottom end members double-seamed thereto, comprising a horizontally disposed chain, vertically disposed pocket members supported at one side of certain of the links and having surfaces adapted to engage the container side walls, pivotally mounted bottom end engaging clamps carried by said members, and means for urging the same downwardly to clamp the containers against said surfaces.

8. A conveyor for a line of containers having cylindrical side walls and bottom end members double-seamed thereto, comprising a horizontally disposed chain, downwardly facing rollers disposed beneath and carried by certain of the links of said chain for supporting the same, vertically disposed pocket members supported at one side of certain of the links and having surfaces adapted to engage the container side walls, pivotally mounted bottom end engaging clamps carried by said members, and means for urging the same downwardly to clamp the containers against said surfaces.

9. A conveyor for a line of containers having cylindrical side walls and bottom end members double-seamed thereto, comprising a horizontally disposed chain, downwardly facing rollers disposed beneath and carried by certain of the links of said chain for supporting the same, vertically disposed pocket members carried by said links and having surfaces adapted to engage the container side walls, pivotally mounted bottom end engaging clamps carried by said members, means for urging the same downwardly to clamp the containers against said surfaces, and a plurality of upper guide wheels carried by said members above said chain.

10. A conveyor for containers having cylindrical side walls and bottom end members secured thereto, comprising a chain and a plurality of container holding assemblies, each assembly comprising a bracket having upper and lower blocks secured to the chain, vertically disposed, arcuate wings connecting the blocks and providing a container side wall engaging surface, downwardly projecting journal means on the lower block, a supporting roller journalled therein, an upwardly projecting stub shaft carried by the upper block, a guide roller journalled thereon, a clamp pivoted on the bracket above said wings, and means for urging the clamp into engagement with a container to urge the same against said surface.

11. A conveyor adapted to move, in inverted position, a line of cans having cylindrical side

walls and bottom end members seamed thereto, said conveyor comprising a chain having upwardly and downwardly projecting flanges carried by certain links thereof, and can holders secured to the flanges, each comprising lower journal means, a supporting roller journalled thereon, a pair of vertically disposed arcuate wings adapted to engage the side wall of a can, upper journal means, an upper guide roller journalled thereon, and a pivoted clamp mounted for swinging movement into engagement with the bottom end of a can to clamp the same against said wings.

12. A conveyor adapted to support, in inverted position, a line of containers having cylindrical side walls and bottom end members secured thereto, comprising a chain, upwardly and downwardly projecting flanges adjacent one side of certain of the links of the chain and container carrying assemblies secured to said flanges, each assembly comprising a bracket secured to the flanges and having a vertically disposed arcuate surface on the opposite side of the chain adapted to engage a container side wall, journal means at the upper and lower ends of the brackets, a guide roll on the upper journal and a supporting roll on the lower journal, and a clamp carried by said bracket and adapted to engage the bottom of a container to urge the side wall thereof into engagement with said arcuate surfaces.

13. In combination, a conveyor trained for movement along a substantially horizontal path and having holders associated therewith for holding containers, such as beer cans, in inverted, neck-down position, a discharge station including means for releasing the containers from the holders and for causing them to tip laterally therefrom, a transfer dial mounted for rotation on a downwardly and outwardly inclined plane adjacent the discharge station and having pockets in its periphery adapted to receive the containers as they are tipped laterally from the holders, means for rotating the dial to move the containers to a position underneath the same in inclined relation, a second conveyor below the dial, and means for stripping the inclined containers from the dial pockets and for positioning them on the last-mentioned conveyor in upright position.

14. Apparatus for handling and conveying a line of containers, such as beer cans, comprising a chute down which the containers roll in horizontal position, a dial journalled on a horizontal axis and rotating in a vertical plane and having horizontally disposed peripheral pockets adapted to receive the containers from the chute, a conveyor below the dial having a plurality of tiltable brackets connected thereto, means for holding the brackets in horizontal position as they pass beneath the dial to receive containers from the pockets therein, a second conveyor trained for movement in parallelism with a portion of the first-mentioned conveyor and having holders associated therewith adapted to support the containers in vertical, inverted, neck-down position, means for swinging the brackets from the horizontal position to a vertical position and for holding them in that position as they move with said holders, whereby the containers in vertical, inverted position may be transferred from the brackets to the holders.

15. A conveyor for a line of containers having cylindrical side walls, conical walls adjacent one of their ends and bottom end members double seamed to their other ends, comprising a hori-

zontally disposed chain, vertically disposed pocket members supported by certain links of the chain and having vertically disposed surfaces adapted to engage the container side walls and transverse abutment surfaces positioned to prevent vertical sliding movement of the containers relative to the first-mentioned surfaces, pivotally mounted

5 clamps carried by the pocket members for engaging the ends of the containers, and means for urging the same to clamp the containers against said vertically disposed surfaces and said abutment surfaces.

WILTIE I. GLADFELTER.
WILLIAM A. SCHMIDT.
